UNITED STATES PATENT OFFICE.

ERNEST L. SMITH, OF SALT LAKE CITY, UTAH.

COMBINED PASS OR FRANK AND RECORD-WRITING FORM.

1,249,531.

Specification of Letters Patent. Patented Dec. 11, 1917.

Application filed April 2, 1915. Serial No. 18,755.

To all whom it may concern:

Be it known that I, ERNEST L. SMITH, of Salt Lake City, in the county of Salt Lake and State of Utah, have invented certain new and useful Improvements in Combined Passes or Franks and Record-Writing Forms, of which the following is a specification.

This invention relates to improvements 10 in forms and devices employed by railroads and other carriers in issuing and writing separate annual or term railroad, steamship, sleeping car or other passes and express or telegraph franks, and which are employed 15 in making a permanent record of such passes or franks as issued in duplicate on card forms prescribed by the Interstate Commerce Commission to be used for such purposes.

One object of the invention is to provide 20 in combination on a single sheet of suitable material a form of this character and a record writing form in such a manner and so arranged that separate passes or franks 25 may be written and duplicate record cards therefor made in carbons in a single writing operation on a typewriter or other writing device.

This object is attained by the use of a 30 pass or frank and record writing form printed and combined on a single sheet of suitable material of the form and arrangement suggested as illustrated in the accompanying drawings in which,

Figure 1 represents a front elevation of 35 a sheet showing a combined pass and record writing form before they are separated;

Fig. 2 represents this improved sheet employed in connection with the record cards, 40 one end of said sheet being turned up to show the record cards and the carbon sheets arranged between them disposed thereunder;

Fig. 3 represents another view of the 45 sheet containing the pass and the data guides with the pass shown partly separated from said sheet.

In the embodiment illustrated, a flat rectangular sheet 1 is shown on which a rectangular-shaped pass or frank and a U-shaped record writing form are printed and combined. The pass 2 which is an integral part of sheet 1 has its boundary indicated at 3 and is printed in the form and arrangement now generally used by carriers for 50 passes and franks, one side edge of the pass 2 coinciding with one side edge of the sheet

1 as shown at 4 in Fig. 1. The boundary 3 is formed by two parallel division lines which extend transversely of the sheet from one side edge thereof to points adjacent the middle of the same, and by another division line which extends longitudinally of the sheet between the two transverse lines. The outline of the pass 2 preferably has round corners as shown at 5.

Printed data guides are shown on the face of sheet 1 outside the boundary line 3 of the pass in the form of printed words shown at 6, which guides are arranged to conform with the printing 7 on the record cards 7 for 65 the corresponding entries thereon. These lettered guides 6 are to be followed when inserting the record data required to be shown by the Interstate Commerce Commission on the faces of the record cards 7, in addition to 70 that written on the pass or frank portion. These record cards 7 correspond in size and shape to the size and shape of the combination sheet 1 and are numbered in duplicate according to the series numbers of the passes 75 or franks and are printed in a form that will permit carbon counterparts of the matter written in the several spaces on the sheet 1 to be transmitted by the use of carbon sheet 8 directly to the record cards 7 in the 80 conforming spaces provided thereon.

The combined pass or frank and writing form sheet 1 herein described is preferably made of fiber or other tough, durable, and pliable material suitable for such purposes, 90 and the size and structure of this sheet 1 may be varied to either increase or decrease the dimensions thereof to adapt it for any desired purpose.

The edges of the pass or frank portion 2 95 indicated by the boundary line 3 are preferably wholly or partially perforated, or are partially cut and partially perforated at the time they are printed, for convenience in separating the pass portion 2 from the 100 remainder of the sheet, but they need not be necessarily so formed but may be merely indicated by lines when printed to facilitate the cutting out of this portion of the sheet by mechanical means when the pass or frank 105 is written or filled out.

These combination sheets 1, the record cards 7, and carbon sheets 8, may be assembled in groups as required or they may be arranged in groups and assembled in the 110 required sets and padded together with tissue sheets 9 inserted to separate the dif-

ferent sets in whatever numbers may be desired, as shown in Fig. 2.

Sheet 1 above described has the printed data guides 6 arranged thereon in spaces 5 conforming to the spacing mechanism of a standard typewriter and to the printing 7' on the record cards 7 to be used in connection therewith.

In use, this combined pass or frank and 10 record writing form sheet 1 is placed in the usual manner in a typewriter together with record cards 7 and carbon sheets 8 properly inserted between them for making counterparts of the matter written on the pass or 15 frank portion of sheet 1 and the additional record data to be written thereon. The pass or frank portion 2 is then filled out in the usual manner after which the additional data to be shown on the record cards is 20 written on the face of the sheet 1 in the spaces opposite the printed data guides 6 outside the boundary of the pass 2 which, by the use of the carbon paper 8, is transmitted and impressed upon the record cards 25 7 in the conforming spaces provided thereon. It will be thus observed that the writing of the pass or frank and the recording thereof on the prescribed record cards 7 is performed in a single operation.

30 After each sheet 1, including the pass portion 2, has been filled out in connection with the record cards, the pass or frank portion is detached therefrom by severing it along the boundary line 3, or a plurality of sheets 35 1 may be first filled out in the manner above described and then assembled in superposed relation, and the pass or frank portions 2 thereof cut out along their boundaries by a suitable cutting machine in the usual manner. The pass or frank portion 2 is preserved and used for the purpose intended 40 and the remainder of sheet 1 having served its purpose of providing means for placing the pass or frank portion of the combined 45 sheet and form in position for filling out and recording the matter written thereon in carbon on the record cards, is discarded and destroyed.

The record cards 7, any desired number of

which may be employed to meet the requirements of the Interstate Commerce Commission, which are completely filled out in the same operation with the printing or filling out of sheet 1 in accordance with the requirements of the Interstate Commerce 55 Commission are preserved intact for record purposes.

I claim:—

A combined pass blank and record writing form to be used in making a permanent 60 record of the pass as issued in duplicate on prescribed card forms and in filling in the other data on the card forms by a single writing operation, comprising a flat rectangular sheet equal in size to the size of the 65 prescribed card forms and having three division lines thereon, two of said lines being parallel to each other and extending transversely of the sheet from one side edge thereof to points adjacent the middle of the 70 sheet, and being spaced equal distances from the end edges of the sheet, the remaining division line extending longitudinally of the sheet between the transverse lines, said 75 division lines dividing said sheet into a rectangular shaped pass blank of convenient size to fit into a pocket book and a U-shaped record writing form, both of which are free of division lines, the pass blank being 80 bounded at its two ends and one side edge by the division lines, the remaining side edge being a portion of the herein mentioned side edge of said sheet, and printed data guides on the pass blank and on the record writing form, said guides being arranged 85 to correspond to those on the aforesaid prescribed card forms so that when the former are filled in by a single writing operation the card forms will be completely filled in 90 duplicate.

In witness that I claim the foregoing I have hereunto subscribed my name this twenty-third day of March, 1915.

ERNEST L. SMITH.
